DESCRIPTION

FIG. 1 is a perspective view illustrating a product packaging bag for sporting equipment;

FIG. 2 is a front view thereof;

FIG. 3 is a left side elevational view thereof;

FIG. 4 is a right side elevational view thereof;

FIG. 5 is a top view thereof;

FIG. 6 is a rear view thereof; and,

FIG. 7 is a bottom view thereof.

The broken line showing of environment in the drawings is for illustrative purposes only and forms no part of the claimed design.
